UNITED STATES PATENT OFFICE.

WARREN D. CLOUGH, EVERETT S. CLOUGH, AND JOHN G. CLOUGH, OF QUINCY, ILLINOIS.

CONCRETE-MIXER.

No. 927,117,

Specification of Letters Patent.

Patented July 6, 1909.

Application filed February 6, 1908. Serial No. 414,530.

To all whom it may concern:

Be it known that we, WARREN D. CLOUGH, EVERETT S. CLOUGH, and JOHN G. CLOUGH, all citizens of the United States, and residents of Quincy, in the county of Adams and State of Illinois, have invented a new and Improved Concrete-Mixer, of which the following is a full, clear, and exact description.

Our invention relates to machinery for working concrete and the like, our more particular purpose being to produce a concrete mixer especially adapted for continuously admixing concrete in successive charges of limited volume.

Reference is to be had to the accompanying drawings forming a part of this specification, in which similar characters of reference indicate corresponding parts in all the figures.

Figure 1 is a substantially central vertical section through our machine complete, on the line 1—1 of Fig. 2, this view showing the main shaft, the engine and gearing for driving the main shaft, the rocking drum and the rocking receiving pan for temporarily holding the materials and delivering them in the form of a charge or batch into the drum, this view further showing a part of the clutch mechanism employed for actuating the delivery pan; Fig. 2 is a fragmentary cross section upon the line 2—2 of Fig. 1, on an enlarged scale, looking in the direction of the arrow, and showing the delivery pan, the sector for tilting the same, the rocking drum, the rack for actuating this drum, and a hand lever used for operating the clutch for controlling the release of the drum; Fig. 3 is a section upon the line 3—3 of Fig. 1, on an enlarged scale, looking in the direction of the arrow and showing more particularly the sector for tilting the receiving pan, the gearing for actuating the sector and a hand-controlled clutch for throwing the sector into and out of action at will, this view further showing the spring used for retracting the sector; Fig. 4 is an enlarged fragmentary section upon the line 4—4 of Fig. 2, looking in the direction of the arrow, and showing the clutch mechanism for throwing into and out of gear the pinion controlling the rack for actuating the rocking drum; Fig. 5 is a fragmentary view of the clutch releasing mechanism controllable by hand for throwing the pinion driving the sector; and Fig. 6 is a fragmentary plan showing a latch for tem-

porarily holding the drum in a predetermined position and controllable by hand for releasing said drum.

A frame 7 having the form of a vehicle body is mounted upon wheels 8, 9. A motor 10, in this instance a gasolene engine, is supported upon the frame and is provided with a fly-wheel 11. Bearings, one of which is shown at 12, support the engine shaft, and 65 bearings 13, 14 support the main shaft 15 of the concrete mixer. A drum 16 is used for holding the charge of concrete while the same is being mixed and for releasing the charge after thorough mixture. Mounted 70 upon the drum is a lug 16^c, and disposed within the path of the lug is a stirrup 16^b attached to the frame, these parts being so arranged that the lug 16^c may lodge against the under side of the stirrup 16^b so as to 75 serve as a limiting stop for the movement of the drum 16 in one direction (see Fig. 3). This drum is provided with collars 17 and 18 encircling the main shaft 15 and fitting loosely thereupon so as to allow the drum to 80 turn independently of the rotation of the shaft.

A number of arms 19 are each provided with a flat portion 20 and are secured rigidly upon the shaft 15 by aid of bolts 20^a. The 85 various arms extending radially from this shaft are staggered relatively to each other, as will be understood from Fig. 1. Each arm 19 carries a mixing plow 21 secured thereto by aid of bolts 22 which extend through slots 90 23. By moving the bolts 22 relatively to the slots 23, the mixing plows can be adjusted so as to compensate for wear upon their edges. A pinion 12^a mounted upon the engine shaft 95 meshes with a gear 12^b upon the main shaft 15, for the purpose of turning the latter when the engine is in action.

Mounted upon the drum 16 is a rack 24 of arcuate form, and meshing with this rack is a pinion 25 for the purpose of causing the drum to rock. The pinion 25 is mounted loosely upon a shaft 26 supported in bearings 26^a. This shaft turns continuously. A clutch 27 is used for throwing the pinion 25 into and out of action. For this purpose a hand lever 105 28 is connected with the clutch 27, in the usual manner of connecting levers with clutches, and is mounted upon a swivel support 29. The lever 28 is operated to shift the clutch 27 by a cam 16^d on the drum 16.

A sprocket wheel 30 is keyed upon the main shaft 15 and a smaller sprocket wheel 110

31 is mounted rigidly upon the shaft 26. Connecting together these sprocket wheels is a sprocket chain 32. A lug 33 is mounted upon the drum 16 and is rounded upon its 5 outer surface, as will be understood from Fig. 2. A latch 34 is disposed partially within the path of this lug and is adapted to be tripped, as indicated by dotted lines in Fig. 2, so as to snap over the lug 33 and thus 10 hold the drum 16 temporarily in a predetermined position. A handle 35 is provided for the latch and is used in releasing the same from engagement with the lug 33. A spring 36 presses continuously upon the handle 35 15 and tends to maintain the latch 34 in its normal position.

Bearings 37, 38 support a rocking shaft 39. Mounted rigidly upon this rocking shaft is a toothed sector 40 provided with a stiffening 20 rib 41. Arms 42 are mounted rigidly upon a rocking shaft 39 and supported upon these arms is a receiving pan 43 provided with cut away portions 44 for facilitating the removal from the receiving pan of materials used in 25 mixing the concrete. The bottom of the receiving pan 43 is provided with slots 43^a and through these slots extend bolts 43^b whereby the pan is adjustably held in position upon the arms 42. In order to adjust the receiving 30 pan or mixing pan 43, the operator loosens the bolts 43^b, pulls the pan out or pushes it in a little, as the case may be, and tightens the bolts. Shields 45 mounted upon cross beams 46 are adapted to be engaged by the arms 42 so as to support these 35 arms when the receiving pan is in position for the materials to be thrown into it (see Fig. 2).

Mounted upon the opposite side of the machine is an angle iron 47 for strengthening the framework. The drum 16 is provided with cupped edges 48 and with a straight or flattened flange 49 extending practically throughout the entire length of the drum and being flush with the cupped edges 48. This 45 flange 49 serves the purpose of a spout for discharging the concrete.

Mounted rigidly upon the sector 40 is a cuneiform cam 50 which is adapted to engage 50 a lug 51 mounted rigidly upon a hand lever 52, so that when the sector 40 reaches a predetermined position it shifts the lever 52. This lever controls a clutch 53 (see Fig. 5) and serves to lock a pinion 54 relatively to the shaft 15, and to unlock the same in the manner well understood in clutch building.

The hand lever 52 is mounted upon a pivot 55 and may be moved by hand for the purpose of causing the clutch 53 to grip and thus 60 throw into action the pinion 54. A powerful retractile spring 56 (see Fig. 3) is connected with the framework and with a chain 57. A chain 58 attached to a lug or projection 59 on the sector 40, connects the chain 57 and the 65 spring with the sector 40. The purpose of

the spring 56 is to retract the sector 40 to its normal position and the chain 57 is to limit the retractile effect of this spring. The chain 58 is normally loose as shown in Fig. 3, but becomes tight soon after the sector 40 begins to rotate in a clockwise direction, according to this figure, and as the chain 58 tightens a tension is gradually thrown upon the spring 56.

The operation of our device is as follows: 75 The motor 10 being in action, motion is transmitted through the pinion 12^a and gear 12^b to the main shaft 15, and the arms 19 are caused to rotate. The mixing plows 21 are thus adapted to stir and thoroughly mix any 80 ingredients which may be contained within the drum 16. Normally this drum occupies the position indicated in Fig. 1, the mixing pan 43 meantime occupying the position indicated in Fig. 2. The materials to be 85 mixed are thrown into the mixing pan 43 and here they may remain until any concrete within the drum 16 is discharged therefrom. The hand lever 28 is normally in such position that the pinion 25, controllable by the 90 clutch 27, runs loose upon the shaft 26. When, however, the hand lever 28 is moved to the right according to Fig. 1, the clutch 27 grips and the pinion 25 becomes rigid upon the shaft 26. This shaft constantly rotating 95 because of the continuous action of the sprocket chain 32, now causes the pinion 25 to turn the rack 24. The drum turns approximately $\frac{1}{4}$ of a revolution so that the cam 16^d (see Fig. 2) carried by the drum is 100 brought against the lever 28. This unlocks the clutch and releases the pinion 25, as will be understood from Fig. 4. The pinion 25 being now idle upon the shaft 26, the drum is, 105 of course, released. The movement just described, constituting approximately $\frac{1}{4}$ of a turn, for the drum, is the movement necessary to discharge the contents of the drum, and leaves the spout 49 in the position indicated by dotted lines substantially at the 110 bottom of Fig. 2. Consequently, the charge of concrete contained within the drum is easily ejected, the direction of rotation of the arms 19 carrying the mixing plows 21 being such as to facilitate the same. The rocking movement of the drum 16, as just described, 115 turns the lug 33 into engagement with the latch 34 which clicks over it and holds the drum firmly in position, preventing its immediate retraction. The operator by pressing downwardly upon the handle 35 withdraws the latch 34 from the lug 33 and this 120 allows the drum to resume its normal position which it easily does in consequence of its own weight. The lug 16^e engages the inner side of the stirrup 16^b and prevents the drum from swinging past its normal position (see Fig. 3). The operator next moves the hand lever 52 so as to cause the clutch 125 53 to grip. This locks the pinion 54 rigidly 130

in relation to the main shaft 15. The pinion 54 now begins to turn and in so doing causes the sector 40 to rock to an extent representing about $\frac{1}{6}$ of a revolution. In doing this, 5 the receiving pan 43 is carried from its position shown in full lines in Fig. 3, to that shown by dotted lines in this figure and the raw materials within the receiving pan 43 are caused to glide into the drum. The 10 rocking movement of the sector 40 stops when the cuneiform cam 50 (see Fig. 3) engages the hand lever 52 so as to disconnect the clutch 53. When this occurs, the pinion 25 being released now turns idly upon the shaft 15 26 and the arcuate sector 24 is no longer held by the pinion 25 and consequently the rack is retracted to its normal position, as above described. The receiving pan 43 is adjustable relatively to the arms 42, the adjustment being accomplished by aid of the bolts 43^b extending through the slots 43^a. By adjusting the receiving pan 43 the size of the individual charges is varied slightly and the general action rendered more satisfactory.

Briefly stated, while the machine is in action the operator merely moves one lever to tilt the drum and eject its contents and he moves another lever to tilt the receiving pan 30 43 and discharge its contents into the drum. A third movement, to wit, that of the handle 35, restores the drum to its normal position after its contents are ejected. The action of the machine is continuous. While workmen 35 are filling the raw materials into the receiving pan, the previous charge is being worked up. The length of time required to fill the receiving pan has no definite relation to the time required for mixing the materials in the drum. 40 Neither has the time for either of the purposes just mentioned any definite relation to the time that the drum is held in fixed position during the act of discharging its contents. It will thus be noted that so far as 45 practicable the loading of the material into the receiving pan, the working of the materials in the drum and the ejection of the mixture from the drum, are entirely separate and independent acts controllable entirely 50 at will.

We have found that mixing plows of the shape shown are very efficient in the matter of making a thorough admixture within a short time, and with a minimum expenditure of power. We find that an apparatus of the kind above described, if made of suitable proportions to be carried around like an ordinary wagon of medium size, has a capacity of from fifty to one hundred and fifty cubic 55 yards per day.

The machine is to a great extent self-cleaning and is not liable to do any pounding. No scraping or flushing is required. The mixing plows keep themselves and the drum as clean 60 as possible and practically free from any con-

tamination. The direction of rotation, as above explained, also assists the discharge from the drum and in so doing saves power and economizes time. The mountings for the various parts are so arranged that the 70 mixer can be placed near the material to be mixed, and the raw material can be loaded into the receiving pan as cheaply as it could be loaded into wheel-barrows, all this being done without interfering in the slightest degree with the work of mixing the charge previously let into the drum.

Having thus described our invention, we claim as new and desire to secure by Letters Patent:

1. A device of the character described, comprising a power driven shaft, a drum for receiving a charge of concrete or the like mounted to rock on said shaft, means mounted on the shaft within the drum for mixing the charge, means for operating the drum from the shaft, means for throwing the operating means out of gear, a tilting receiving pan for holding a charge of the materials to be mixed, means for operating the pan from the said shaft, and means for throwing the pan operating means out of gear.

2. In a device of the character described, a revoluble shaft, a drum mounted on the shaft to rock, a mixing device on the shaft 95 in the drum, a counter-shaft, means for operating the counter-shaft from the first named shaft, means for rocking the drum from the counter-shaft, a clutch for throwing the drum operating means out of gear, a 100 hand lever for operating the clutch in one direction and a cam on the drum for engaging the lever to operate it in the other direction.

3. In a device of the character described, a revoluble shaft, a drum mounted to rock, a counter-shaft, a receiving pan mounted on the counter-shaft, and adapted to discharge into the drum, gearing between the counter-shaft and the first named shaft for rocking said counter-shaft, a clutch for throwing the pan operating means out of gear, a lever for operating the clutch, and means carried by the counter-shaft for automatically operating said lever.

4. In a device of the character described, a revoluble shaft, a pinion on the shaft, a drum mounted to rock, a counter-shaft, a sector on the counter-shaft and meshing with pinion of the first named shaft, a receiving pan carried by the counter-shaft, and means for returning the sector to normal position.

5. In a device of the character described, a revoluble shaft, a pinion on the shaft, a drum mounted to rock, a counter-shaft, a receiving pan carried by the counter shaft, a sector on the counter-shaft and meshing with the pinion of the first named shaft, a spring having one end secured to a fixed

support, and a flexible connection between the other end of the spring and the sector.

6. In a device of the character described, a rocking drum, a revoluble shaft having a 5 pinion, a counter-shaft, a receiving pan carried by the counter-shaft, a sector on the counter-shaft and meshing with the pinion of the first named shaft, means for returning the sector to normal position, a clutch for 10 throwing the pinion in and out of mesh with the sector, a lever for operating the latch, and a cam on the sector for operating the lever.

7. The combination of a drum for mixing 15 materials, a shaft for actuating said drum, a sector disposed adjacent to said drum, a pinion meshing with said sector and mounted upon said shaft supporting said drum, a clutch for rendering said pinion idle or fixed 20 relatively to said shaft, a receiving pan connected with said sector and adapted to be tilted thereby so as to discharge materials from said receiving pan into said drum, and mechanism controllable by movements of 25 said sector for disconnecting said clutch mechanism when said receiving pan reaches its limit of movement.

8. The combination of a rocking drum, means for mixing materials therein, mechan-

ism for turning said drum for the purpose of 30 ejecting said materials therefrom, a lug mounted upon said drum, a latch for engaging said lug and holding said drum temporarily in a predetermined position, and a handle for controlling said latch. 35

9. The combination of a drum, mechanism mounted therein for mixing materials, a sector for actuating said drum, a spring connected with said sector for retracting the latter, means for turning said drum, and 40 mechanism controllable by movements of said sector for disconnecting said last-mentioned means when said drum reaches a predetermined point in its revolution.

In testimony whereof we have signed our 45 names to this specification in the presence of two subscribing witnesses.
